(57) **CLAIM**

The ornamental design for an injector device, as shown and described.

DESCRIPTION

FIG. 1 is a perspective view of an injector device, showing my new design.

FIG. 2 is a front view of FIG. 1.

FIG. 3 is a back view of FIG. 1.

FIG. 4 is a left-side view of FIG. 1.

FIG. 5 is a right-side view of FIG. 1.

FIG. 6 is a bottom view of FIG. 1.

FIG. 7 is a top view of FIG. 1; and,

FIG. 8 is an enlarged view of the display on the front of the injector device of FIG. 1.

Portions of the injector device shown in broken lines form no part of the claimed design.
